F. J. SCHISLER
HEADLIGHT RECTIFIER
Filed Sept. 24, 1923

UNITED STATES PATENT OFFICE.

FRANK J. SCHISLER, OF WINTHROP, MINNESOTA.

HEADLIGHT RECTIFIER.

Application filed September 24, 1923. Serial No. 664,521.

To all whom it may concern:

Be it known that I, FRANK J. SCHISLER, a citizen of the United States, residing at Winthrop, in the county of Sibley and State 5 of Minnesota, have invented certain new and useful Improvements in Headlight Rectifiers; and I do declare the following to be a full, clear, and exact description of the invention, such as will enable others skilled in 10 the art to which it appertains to make and use the same.

My invention aims to provide a simple and inexpensive, yet an exceptionally effective device to prevent blinding glare from 15 automobile or other headlights, above a predetermined plane, while permitting unobstructed projection of light rays below such plane.

A further object is to provide a device 20 which will shield substantially the lower half of the headlight reflector and the upper portion of the bulb, the bulb shield being so mounted as to be movable aside when changing bulbs.

25 With the foregoing in view, my invention resides in the novel subject matter herein-after described and claimed, the description being supplemented by the accompanying drawings.

30 Figure 1 is a front elevation of an automobile headlight equipped with my invention.

Figure 2 is a vertical sectional view as indicated by line 2-2 of Fig. 1.

35 Figure 3 is a horizontal sectional view taken substantially on line 3-3 of Fig. 1.

Figure 4 is a detail sectional view showing a slightly different form of construction.

40 Figure 5 is a horizontal sectional view on approximately the plane of line 5-5 of Fig. 4.

In the drawings above briefly described, the numeral 1 designates a well-known form 45 of automobile headlight, said headlight having a detachable rim 2 carrying a lens 3 which, due to the present invention, may be of plain clear glass. The headlight is provided with the usual parabolic reflector 4, bulb socket 5, and bulb 6.

Covering substantially the lower half of 50 the reflector 4, is a non-reflecting cover 7 whose lower edge is held in place by the lens 3 or some part associated therewith, 55 while the upper edge of said reflector is provided with a central seat 8 for the bulb

socket 5. On opposite sides of the seat 8, the upper edge of the cover 7 is preferably bowed upwardly as indicated at 9, with the end portions of said edge declining from the bows. The front face of the cover 7 is preferably painted black although it could otherwise be treated to produce a non-reflecting surface and it has been found that by constructing this cover in the manner shown, 60 no blinding rays of light will be projected from the light reflector, above a predetermined plane. Below this plane, however, the reflected rays are projected uninterruptedly to adequately illuminate the highway. 70

I preferably associate a bulb shield with the cover 7. In the present showing, a pair of bendable arms 10 are secured by rivets or the like 11 to the cover 7, at opposite sides of the seat 8, said arms curving downwardly 75 and then upwardly to extend under the bulb 6 and to straddle the usual tip 12 of the latter. The upturned ends of these arms 10 are connected by an arched bulb shield 13 which is preferably integral therewith and 80 is intended to lie in close proximity to the upper front portion of the bulb 6, over its tip 12. This shield prevents the projection of blinding rays directly from the bulb, and the inner side of said shield, as well 85 as the inner sides of the arms 10, preferably have reflecting surfaces, to direct the rays of light backwardly against the uncovered portion of the reflector. Attention may here 90 be directed to the fact that the arms 10 are 90 bendable, permitting the shield 3 to be adapted to different size headlight bulbs as well as permitting said shield to be moved aside when one bulb is being removed and another inserted. 95

The construction above described is common to both forms of the invention which have been illustrated. In addition to these features of construction, the device shown in Figs. 4 and 5, is provided with a yoke 100 14 which is preferably integral with the cover 7, said yoke being adapted to extend over the bulb socket 5, and to be bent down upon the latter to frictionally anchor the rear end of said cover. 105

By providing the construction shown and described or a substantial equivalent thereof, a device is provided which may be easily and inexpensively manufactured from sheet metal, yet regardless of simplicity, the 110 device is highly efficient and desirable. As excellent results have been obtained from the de-

tails disclosed, they may well be followed, but within the scope of the invention as claimed, numerous minor changes may be made.

5 I claim:

1. A headlight rectifier comprising a non-reflecting cover for substantially the lower half of a headlight reflector, a pair of arms extending forwardly from the upper edge of 10 said cover for disposition under the headlight bulb, the front ends of said arms be-

ing curved upwardly for location at the lower front portion of the bulb, and a shield extending between and carried by the up-turned ends of said arms to shield the upper front portion of the bulb. 15

2. A structure as specified in claim 1; said arms and shield having reflecting surfaces at their inner sides.

In testimony whereof I have hereunto affixed my signature.

FRANK J. SCHISLER.
